(57) **CLAIM**

The ornamental design for a jump rope with thickened section, as shown and described.

DESCRIPTION

FIG. 1 is a front elevation view of a jump rope showing the new design.

FIG. 2 is a top plan view thereof.

FIG. 3 is a rear left side perspective view thereof; and,

FIG. 4 is a right side elevation view thereof.

The broken lines showing the handles are illustrative of environmental structure only, and form no part of the claimed design.
